UNITED STATES PATENT OFFICE

2,688,715

SURGE DIVERTER

Svend Aage Vörts and Erland Bertil Nilsson,
Ludvika, Sweden, assignors to Allmanna
Svenska Elektriska Aktiebolaget, Västerås,
Sweden, a Swedish corporation

Application May 26, 1950, Serial No. 164,355

Claims priority, application Sweden June 18, 1949

3 Claims. (Cl. 317—70)

1

Modern surge diverters usually consist of a series of spark gaps in series with a valve resistor, usually consisting of blocks of a material with voltage dependent resistance. At high voltages, these parts have been enclosed in a series of tubular insulators. The number of insulators or units arranged above each other is determined by the line voltage. As the spark gaps moreover are generally connected in parallel with controlling resistors, an even voltage stress is obtained on the spark gaps at low steepness of the wave front of the over-voltages, but at high steepness, the voltage distribution is determined by the capacity conditions. This causes a lower ignition voltage on the whole series of spark gaps at high steepness than at a low one. By itself it is not inconvenient if the decrease of the ignition voltage only sets in at a considerably high steepness. If, however, the decrease of the ignition voltage sets in at a low steepness, it is possible that the surge diverter is ignited at normally occurring switching over-voltages, which generally is not desirable.

By the uneven voltage distribution also the extinguishing ability of the whole series of spark gaps is lowered as a consequence of the fact that if a spark gap in the series is not capable of withstanding the recovery voltage, it re-ignites, with the result that also the following spark gap ignites, and so on, until the whole series has ignited. Also by this reason it is desirable that the even voltage distribution is maintained up to considerably high steepness.

The present invention relates to a surge diverter, especially for high voltages in which the above mentioned uneven voltage distribution is considerably equalised, and it is characterised in that the total number of spark gaps in the diverter is distributed on the different units in approximate proportion to the natural voltage distribution along the diverter, i. e. the voltage distribution which is caused by the capacity conditions. By this means, the voltage stresses on all the spark gaps will be about the same.

The invention will be best understood with reference to the accompanying drawing, in which Figure 1 shows a section through the surge diverter, whereas Figure 2 shows a diagram of the voltage distribution.

In Figure 2, the dash-line curve shows the approximate voltage distribution along a pile of insulators according to Figure 1, without precautions for voltage equalisation, whereas the full-line curve shows the voltage distribution along the insulators according to the arrange-

2

ment shown in Figure 1, and the chain-line curve represents the voltage distribution inside the insulators, i. e. along the resistors and piles of spark gaps, before the diverter has ignited.

5 In the form of the invention shown in the drawing, 1 designates the insulator cylinders piled on each other and held together by means of metal flanges 2. A connecting terminal for the line is denoted 3, and 4 is a voltage equalising metal ring which by means of arms 5 is supported by the top flange 2. Inside the insulators 1, piles of spark gaps 6 are arranged, in series with which in every unit are arranged piles of voltage dependent resistor blocks 7. The bottom unit contains only

15 such voltage dependent resistors.

Because of the fact that the insulators may become outwardly conductive owing to dust or moist coating, it is possible to obtain a voltage distribution across the different units, not corresponding to the normal voltage distribution, and thus neither to the distribution of the spark gaps. This may cause an overstrain of the spark gaps in the units which contain a smaller number of spark gaps. According to the invention, this is 20 prevented by adapting the effective external length of the insulators to the number of spark gaps in the diverter units by outwardly short-circuiting part of them. In the form shown, this is obtained by providing the outside of the insulators at a suitable height with a bandage 8, 25 conductively connected with the flanges 2 at the lower part of the insulators. This bandage may 30 of course be substituted by metallising or some other conducting covering.

It is not necessary that all units contain spark gaps, but in some cases it may be convenient to connect one or several units, only containing resistors, in series with units containing spark gaps.

35 We claim as our invention:

40 1. A surge diverter comprising a plurality of insulator cylinders piled upon each other, conducting flanges joining said cylinders, voltage dependent resistors in said cylinders, and a number of series connected combined switching and 45 quench spark gaps of equal length in each cylinder in series with said resistors, said number being different in each cylinder and accommodated to the voltage falling on each cylinder due to the natural capacitive voltage distribution at the appearance of a voltage surge.

50 2. A surge diverter comprising a plurality of insulator cylinders piled upon each other, conducting flanges joining said cylinders, voltage dependent resistors in said cylinders, a number of

55 55

series connected combined switching and quench spark gaps of equal length in each cylinder in series with said resistors, said number being different in each cylinder and accommodated to the voltage falling on each cylinder due to the natural capacitive voltage distribution at the appearance of a voltage surge, and metallic shields outside part of the cylinders each shield short-circuiting the external surface of a part of the cylinder outside the resistors.

3. A surge diverter comprising a plurality of insulator cylinders piled upon each other, conducting flanges joining said cylinders, voltage dependent resistors in said cylinders, a number of series connected combined switching and quench spark gaps of equal length in each cylinder in series with said resistors, said number being different in each cylinder and accommodated to the voltage falling on each cylinder due to the natural capacitive voltage distribution at the appearance of a voltage surge, and metallic shields outside

part of the cylinders each shield short-circuiting the external surface of the part of the cylinder outside the resistors, said shields consisting of a metal bandage.
